UNITED STATES PATENT OFFICE.

NICHOLAS SCHUSTER, OF WESTMINSTER, LONDON, ENGLAND.

REGENERATIVE COKE-OVEN.

1,193,830.

Specification of Letters Patent.

Patented Aug. 8, 1916.

Application filed December 21, 1914. Serial No. 878,419.

To all whom it may concern:

Be it known that I, NICHOLAS SCHUSTER, subject of the Emperor of Germany, residing at 7 Princes street, in the city of Westminster, London, England, have invented certain new and useful Improvements in Regenerative Coke-Ovens, and of which the following is a specification.

This invention relates to coke ovens of the regenerative type, in which the regenerative tunnels are formed in the base of the structure, and the objects of the invention are to so construct the regenerative tunnels and so connect the same with the various flues and passages of the structure in the manner hereafter described, that equal heating of the whole foundation and more equal expansion and contraction of the structure are secured than heretofore, and this with a less deep foundation.

According to this invention I arrange the regenerative tunnels in two pairs, parallel to each other in the foundation of the structure. The regenerative tunnels so arranged are themselves divided into chambers by transverse walls, and communicating passages are formed between the tunnel chambers and those passages which alternatively serve as exit flues for the products of combustion and air inlet passages, so that the products of combustion pass from one heating chamber in the side wall dividing two ovens, into one chamber of a tunnel forming one of a pair, while the products of combustion form the heating chamber in the next side wall pass into one chamber of the other tunnel of the pair. With respect to the other pair of tunnels, the corresponding chambers of these are similarly connected with half of the number of the heating flues in corresponding side walls dividing the ovens so as to either supply heated air thereto or to carry off products of combustion.

The invention will be described with reference to the accompanying drawings.

Figure 1 is a longitudinal section of the right hand half of the structure, this section being taken through the heating flues in one of the side walls between two ovens, and Fig. 1^A shows the left hand half of the same coke oven, this section being taken through the adjacent coking chamber. Fig. 2 is a transverse vertical section of the structure taken about the line X-Y of Fig. 1^A and drawn to a slightly larger scale than the lat-

ter figure. Fig. 3 is a horizontal section taken about the line X¹-Y¹ of Fig. 2. Fig. 4 is a horizontal section through the regenerators and tunnels 19 and 20.

Referring to the drawings, in the base of the structure below the coking chambers 1 and extending transversely relatively thereto, are built two pairs of regenerative tunnels 2, 3 and 4, 5, and each pair of regenerative tunnels are similarly divided by transverse walls into regenerative chambers; thus the tunnel 2 is divided by the transverse walls 6 as shown in full lines at Fig. 2 and by dotted lines at Fig. 3, while the other tunnel 3 completing the pair is divided by the walls 7 which are intermediate in the plan view between the walls 6 of the tunnel 2. The other pair of regenerative tunnels 4, 5 are similarly divided as will be observed by an inspection of the drawings. All these chambers in the tunnels are fitted with checker brick work as is usual.

The side walls of the coking chambers 1 are each formed with a heating chamber 8 divided in the example shown into vertical heating flues 9, Fig. 1, and each heating flue 9 communicates at its base with a gas supply passage or passages 10 into which gas passes from a main 11 through a pipe 12 controlled by a cock or cocks 13, and the gas supply passage or passages 10, shown in full lines at Fig. 1, extends through half the length of the side wall and supplies half the number of heating flues 9 in that heating chamber, while an exactly similar gas supply system supplies the other half of the number of heating flues 9 in the same side wall, and when gas is admitted, by for instance the gas supply system shown in full lines at Fig. 1, to half the number of heating flues in the side wall, the gas supply system for the other half of the flues in that side wall is closed by the cock or cocks 13.

Beneath the sole of each coking chamber 1 and extending parallel therewith is a passage 14 divided centrally of its length, and half the number of vertical heating flues 9 in one side wall communicate by base passages 15 with one part of their corresponding passage 14, and the other half of the vertical heating flues 9 in that side wall communicate with the other part of the corresponding divided passage 14, by similar passages 15.

Considering the left hand portion of the

vertical section at Fig. 1^A, that part of the passage 14 there shown in full lines, communicates by a passage 16 with the upper part of one of the regenerative chambers in the tunnel 2, while the next similar passage 14, beneath the next coking chamber, communicates by a passage 17 with the upper part of a chamber in the regenerative tunnel 3. Each regenerative chamber of the tunnel 2 communicates by a passage 18, and each regenerative chamber of the tunnel 3 communicates by a passage 18^x, with a waste heat flue 19, which can be connected by any suitable or well known dampers, valves or the like either with the main uptake for the products of combustion, or with the open air, as may be required. The other pair of regenerative tunnels 4, 5 are similarly arranged and connected, with the waste heat flue 20 and with the parts of the passages 14 extending half the width of the structure above the said tunnels 4, 5.

21 and 22 are regulating valves governing the passages 18, 18^x from the regenerative chambers of the tunnels to the waste heat flues 19, 20.

23 are air passages, Figs. 2 and 3, extending entirely through the structure upon each side and parallel with the gas passages 10. The provision of such passages and the construction of the gas passages form the subject matter of my patent application No. 878,420, of even date herewith, and therefore are not further dealt with in this specification.

The description of the invention will be rendered more complete by describing the course of the products when the ovens are in operation. Considering Figs. 1 and 1^A of the drawings, it will be assumed that gas is being supplied through the gas passages 10 on the right hand side of the drawing Fig. 1, and consequently the fifteen vertical heating flues 9 in the half of the structure Fig. 1 shown by way of example, are being supplied with gas. Simultaneously the waste heat flue 20, Fig. 1, is open to the atmosphere and air passes by the passages 18, 18^x to all the chambers of the regenerative tunnels 4, 5, which tunnels are in a heated condition by products of combustion having previously passed through them. The air so admitted becomes heated by passing through the checker brick work in the chambers of the regenerative tunnels 4, 5, and the heated air passes through passages 16^x, Fig. 3, from adjacent chambers of the tunnel 5 to alternate passages 14 beneath the right hand half of the structure shown at Fig. 1, while heated air passes by passages 17^x from adjacent chambers of the regenerative tunnel 4 to the remaining passages 14 beneath the right hand half of the structure Fig. 1, so that one passage 14 beneath the right hand

heated air from one chamber of a tunnel, such as 4, while the next passage 14 is supplied with heated air from a chamber of the other tunnel 5 of the pair. Heated air passes from the passages 14 in the right half of the structure through the passages 15 to the base of the heating flues 9, where the air and gas commingle and combustion takes place. The products of combustion pass in the direction of the arrows Fig. 1, to the left hand half, Fig. 1^A, where they pass down the vertical heating flues in the said left hand half, and so by way of the passages 15 into the passages 14, and from thence by the passages 16 and 17 to the upper parts of the regenerative chambers in the pair of tunnels 2, 3, from whence the products of combustion pass away by the passages 18, 18^x to the waste heat flue 19, which at this time is in connection with the main uptake. Obviously when the waste heat flue 19 is disconnected from the uptake and open to the atmosphere, while the waste heat flue 20 is connected to the uptake, and also the gas supply cocks 13 on the right hand side of Fig. 1, are closed, and those on the left hand side, Fig. 1^A, opened, the flow of the gas will be reversed.

By this invention I am enabled to provide regenerative chambers of considerable cubical capacity and length for each of the heating chambers of the side walls, whereas if instead of the pairs of regenerative tunnels so outlined, two single regenerative tunnels were employed, the same length of regenerative chamber and cubical capacity of same could not be allowed without weakening the structure, introducing unequal heating of the substructure and greatly increasing the depth of the substructure.

What I claim as my invention and desire to secure by Letters Patent is:—

1. A regenerative coke oven, comprising a structure having a series of separate coking chambers formed therein parallel to each other, the side walls of said coking chambers each having a heating chamber formed therein, means for supplying gaseous fuel to either end required of each heating chamber, said structure having formed in the base thereof two pairs of tunnels, walls in said tunnels to divide them each into a plurality of regenerative chambers of a number equal to half the number of heating chambers in the oven side walls, said structure having communicating passages connecting one half of each heating chamber in one side wall to one of the chambers in one tunnel of one pair, and communicating passages connecting the other half of said chamber in said side wall with one of the regenerative chambers in one tunnel of the other pair, and having passages connecting the two halves of the next heating chamber respectively with a regenerative chamber in the

other tunnel of each pair, two flues calculated to be connected either to an uptake or open to the atmosphere, and passages connecting each chamber of one pair of tunnels to one of said flues, and passages connecting each chamber of the other pair of tunnels to the other of said flues.

2. A regenerative coke oven, comprising a structure having a series of separate coking chambers formed therein parallel to each other, the side walls of said coking chambers each having a heating chamber formed therein and extending the length thereof, means for supplying gaseous fuel to one end part or the other end part of each heating chamber as required, said structure having formed in the base thereof two parallel pairs of tunnels extending transversely relatively to said coking chambers, walls in said tunnels extending transversely to the length thereof to divide each of said tunnels into a plurality of regenerative chambers of a number equal to half the number of heating chambers in the oven side walls, said structure having communicating passages connecting one half of each heating chamber in one side wall to one of the chambers in one tunnel of one pair, and communicating passages connecting the other half of said chamber in said side wall with one of the regenerative chambers in one tunnel of the other pair, and having passages connecting the two halves of the next heating chamber respectively with a regenerative chamber in the other tunnel of each pair, two flues calculated to be connected either to an uptake or open to the atmosphere, and passages connecting each chamber of one pair of tunnels to one of said flues, and passages connecting each chamber of the other pair of tunnels to the other of said flues.

3. A regenerative coke oven, comprising a structure having a series of separate coking chambers formed therein parallel to each other, the side walls of said coking chambers each having a heating chamber formed therein and extending the length thereof, means for supplying gaseous fuel to either end required of each heating chamber, said structure having two separate horizontal passages beneath the sole of each coking chamber, one of said horizontal passages communicating with one end part of the heating chamber in a side wall, and the other horizontal passage communicating with the other end part of said heating chamber in the same side wall, said structure having formed in the base thereof two pairs of tunnels, walls in said tunnels to divide them each into a plurality of regenerative chambers of a number equal to half the number of heating chambers in the oven side walls, a passage in said structure connecting one of said horizontal passages beneath the sole of a coking chamber to one of the heating chambers in one tunnel of one pair, and a passage in said structure connecting the other horizontal passage beneath the sole of said coking chamber with one of the regenerative chambers in one tunnel of the other pair, and said structure having passages connecting the two horizontal passages beneath the sole of the next coking chamber respectively with the regenerative chamber in the other tunnel of each pair, two flues calculated to be connected either to an uptake or open to the atmosphere, and passages connecting each chamber of one pair of tunnels to one

of the heating chambers in one tunnel of one pair, and a passage in said structure connecting the other horizontal passage beneath the sole of said coking chamber with one of the regenerative chambers in one tunnel of the other pair, and said structure having passages connecting the two horizontal passages beneath the sole of the next coking chamber respectively with the regenerative chamber in the other tunnel of each pair, two flues calculated to be connected either to an uptake or open to the atmosphere, and passages connecting each chamber of one pair of tunnels to one of said flues, and passages connecting each chamber of the other pair of tunnels to the other of said flues.

4. A regenerative coke oven, comprising a structure having a series of coking chambers formed therein parallel to each other, the side walls of said coking chambers each having a heating chamber formed therein and extending the length thereof, vertical divisions in said heating chamber extending from the base thereof but not extending to the top of said chamber to form heating flues therein, means for supplying gaseous fuel to the bases of half the number of said heating flues in said chamber at one end thereof or for supplying gaseous fuel to half the number of said heating flues at the other end thereof as required, said structure having two separate horizontal passages beneath the sole of each coking chamber, one of said horizontal passages communicating with half the number of said heating flues in said heating chamber toward one end of a side wall, and the other horizontal passage communicating with the heating flues in said heating chamber in the same side wall and near the other end thereof, said structure having formed in the base thereof two pairs of parallel tunnels adjacent to each other and extending at right angles to the lengths of the coking chambers, walls in said tunnels to divide them each into a plurality of regenerative chambers of a number equal to half the number of heating chambers in the oven side walls, a passage in said structure connecting one of said horizontal passages beneath the sole of a coking chamber to one of the heating chambers in one tunnel of one pair, and a passage in said structure connecting the other horizontal passage beneath the sole of said coking chamber with one of the regenerative chambers in one tunnel of the other pair, and said structure having passages connecting the two horizontal passages beneath the sole of the next coking chamber respectively with the regenerative chamber in the other tunnel of each pair, two flues calculated to be connected either to an uptake or open to the atmosphere, and passages connecting each chamber of one pair of tunnels to one

of said flues, and passages connecting each chamber of the other pair of tunnels to the other of said flues.

5. A regenerative coke oven, comprising a structure having a series of separate coking chambers formed therein parallel to each other, the side walls of said coking chambers each having a heating chamber formed therein, means for supplying gaseous fuel to either one end half or the other end half of each heating chamber as required, said structure having formed in the base thereof two pairs of tunnels parallel to each other and extending at right angles to the lengths of the coking chambers, transversely extending walls in said tunnels to divide them each into a plurality of regenerative chambers of a number equal to half the number of heating chambers in the oven 20 side walls, said transversely arranged walls in one tunnel of a pair of tunnels being in a

plane passing centrally between two opposite walls in the other tunnel of the pair, and communicating passages connecting the other half of said chamber in said wall with one of the regenerative chambers in one tunnel of the other pair, and having passages connecting the two halves of the next heating chamber respectively with a regenerative chamber in the other tunnel of each pair, 25 two flues calculated to be connected either to an uptake or open to the atmosphere, and passages connecting each chamber of one pair of tunnels to one of said flues, and passages connecting each chamber of the other 30 pair of tunnels to the other of said flues. 35

In witness whereof I have hereunto set my hand in the presence of two witnesses.

NICHOLAS SCHUSTER.
